UNITED STATES PATENT OFFICE.

HERBERT DANIEL STENSON, OF CHELSEA, MASSACHUSETTS.

POULTRY-FEEDER.

1,316,117.

Specification of Letters Patent. Patented Sept. 16, 1919.

Application filed February 13, 1918. Serial No. 217,016.

To all whom it may concern:

Be it known that I, HERBERT D. STENSON, a citizen of the United States, residing at Chelsea, in the county of Suffolk and State 5 of Massachusetts, have invented certain new and useful Improvements in Poultry-Feeders; and I do hereby declare the following to be a full, clear, and exact description of the invention, such as will enable others 10 skilled in the art to which it appertains to make and use the same.

The present invention relates to new and useful improvements in poultry feeders of that type including a storage reservoir for 15 the feed and means associated with said reservoir for opening the discharge mouth thereof at a predetermined time of feeding whereby to eliminate the necessity of personal attention to the feeding operation at 20 the time of feeding.

It is more particularly an object to provide an arrangement whereby an ordinary alarm clock may form a major portion of the releasing mechanism, and wherein the 25 ordinary alarm winding key may, by its rotation at a previously set time release a deterrent member to procure opening of the discharge mouth of the receptacle.

With the above and other objects and advantages in view, the invention resides more particularly in the novel combination, formation and arrangement of parts herein-after described and particularly pointed out in the appended claims.

35 In the accompanying drawings:

Figure 1 is a perspective view of an automatically operated poultry feeder embodying the present invention.

Fig. 2 is a plan view thereof.

40 Fig. 3 is a vertical sectional view thereof.

Fig. 4 is a perspective view of the winding key of the alarm clock and the deterrent member.

45 Referring now more particularly to the drawings, there is provided a main cylindrical storage receptacle 5 having its lower portion taperingly reduced at 6 and terminating in a section 7 of rectangular cross 50 section in which is slidably mounted a valve plate 8 which is supported by in-turned edges 9 of three walls of the section. The receptacle is provided with a suitable cover 10 and with a bail 11 whereby it may be

carried from place to place, and suspended 55 from a suitable support in discharge position.

Suspended by a pair of links 12 pivotally depending from the lower section 7 of the receptacle is a bell-shaped spreader 13, the 60 flaring walls of which are adapted to deflect the feed as it falls from the receptacle and thus spread it over a large space whereby it is accessible to all of the poultry to be fed. Secured to one side of the 65 body portion 5 of the receptacle is a clock supporting bracket formed of a single plate 14 bent in U-shape and having attaching tongues 15 bent outwardly from one of its side edges for securement to the wall of the 70 receptacle, and retaining flanges 16 bent from the other sides thereof. Seated on the right portion of the bracket plate is a clock 17 which is confined against accidental displacement by the sides of the bracket 75 plate and the flanges 16. Pivoted at an intermediate point to one of the side flanges 16 is a lever 18 which has a relatively long arm at one side of its pivot extending diagonally of the bracket and provided with a weight 20 at its outer extremity, and which is connected at its other end with the valve plate 8 by a flexible connection 21 passed through an eye 22 at the outer end of an arm 23 projecting laterally from the 80 lower portion 7 of the receptacle, whereby rocking movement of the lever by the weight 20 thereof may procure a sufficient direct outward pull on the valve plate 8 to open the bottom of the section 7 and permit 85 discharge of the feed. Projecting inwardly from the weight carrying portion of the lever 18 is a detent finger 24 which is engageable with the alarm winding key 25 of the clock, which is disposed with its face 90 toward the receptacle.

In setting the device, the alarm is set at the time at which it is desired to release the feed, and the alarm mechanism is wound up, leaving the key in a horizontal position 100 supporting the pin 24 which is disposed adjacent and to one side of the axis of the key. As the alarm mechanism is actuated, the key rotates in unwinding of the alarm spring, which releases the detent finger, 105 permitting the lever to swing under influence of the weight 20 and open the discharge mouth of the receptacle.

To reset the device, the lever is swung upwardly at its weighted end, the clock is wound and the detent finger again seated on the alarm key, the slide being pushed inwardly to close the discharge mouth of the receptacle.

What is claimed is:

- 10 1. A device of the class described comprising a receptacle having a discharge mouth, a sliding valve for the discharge mouth, a guide carried by the receptacle, a bracket carried by the receptacle and including a bottom and a vertical wall, a lever pivoted between its ends to the said wall for vertical movement, one end of said lever extending outwardly beyond the wall and the other end of said lever extending inwardly longitudinally of the bottom of the bracket and in a plane thereabove, an alarm clock including a flat revoluble winding key disposed upon the bracket, a lateral pin carried by the arm and disposed for engagement upon the winding key when the latter is in horizontal position to hold the lever against pivotal movement, a weight carried by the extremity of the lever beyond the pin, and a flexible element secured to the outer end of the lever and to

- 25

the sliding valve and trained through the guide.

2. A device of the class described comprising a receptacle having a discharge mouth, and a valve comprising a horizontally sliding flat plate for controlling the flow from the discharge mouth, a bracket 30 formed of another plate of suitable shape and secured to the receptacle and having in-turned flanges thereon for supporting and centering an alarm clock, an alarm clock disposed upon the bracket and including an 35 alarm winding key, a weighted lever pivoted to one of said flanges, a detent pin near the end portion of said lever and engageable with the alarm winding key of the clock, for holding said end portion of 40 the lever in raised position and releasable at a predetermined time by rotation of said key, and a connection between the other end portion of the lever and the valve for 45 opening the latter upon a pivotal movement 50 of the lever.
